STEPHEN A. GOODSON, ^{Inventor}

By *Franklin D.* ^{Attorney}

UNITED STATES PATENT OFFICE.

STEPHEN A. GOODSON, OF HILLSBORO, ILLINOIS.

BEET TOPPER.

1,420,482.

Specification of Letters Patent. Patented June 20, 1922.

Application filed September 1, 1920. Serial No. 407,324.

To all whom it may concern:

Be it known that I, STEPHEN A. GOODSON, a citizen of the United States, residing at Hillsboro, in the county of Montgomery and State of Illinois, have invented certain new and useful Improvements in Beet Toppers; and I do hereby declare the following to be a full, clear, and exact description of the invention, such as will enable others skilled in the art to which it appertains to make and use the same.

This invention relates to new and useful improvements in beet toppers and has for its primary object the provision of means for raising the beet tops off of the ground and guiding the same into engagement with a knife.

Another object of this invention is the provision of a combined knife supporting means and guide for the beet tops and which is adapted to adjust itself both vertically and laterally of the device so as to follow a row of beets and adjust itself as to the height and size of the various beets.

A further object of this invention is the provision of means for forcing and holding the beet tops into engagement with the knife.

A further object of the invention is the provision of means whereby the driver or operator may easily guide the device and cause it to travel at an angle to the line of draft power so that a row of beets may be easily followed.

A still further object of this invention is the provision of a beet topper of the above stated character which will be simple, durable and efficient, and which may be manufactured and sold at a comparatively low cost.

With these and other objects in view, as will become more apparent as the description proceeds, the invention consists in certain novel features of construction, combination, and arrangement of parts as will be hereinafter more fully described and claimed.

For a complete understanding of my invention, reference is to be had to the following description, and accompanying drawings, in which:

Figure 1 is a side elevation illustrating a beet topper constructed in accordance with my invention,

Figure 2 is a front elevation illustrating the same,

Figure 3 is a top plan view illustrating the same,

Figure 4 is a longitudinal sectional view taken on line 4—4 of Figure 3, 60

Figure 5 is a detail view illustrating the guide means and the knife,

Figure 6 is a detail view illustrating the reel.

Referring in detail to the drawings, the numeral 1 indicates a platform having rearwardly extending arms 2, to which an arcuate shaped seat support 3 is secured. The seat support carries an ordinary seat 4 at a point rearward of the platform. The platform 1 has side portions 5, to the rear corners of which are secured downwardly extending rods 6 that are bent to extend rearwardly and laterally to form axles 7 on which are journaled ground wheels 8; 75 thus it will be seen that the axles co-operate with the platform in permitting the device to straddle a row of beets. Braces 9 are secured to the lower ends of the vertical rods 6 and to the forward corners of the side portions 5 of the platform 1 to provide a substantial construction. A draft tongue 10 has its rear portion enlarged as illustrated at 11 and pivoted to the platform 1 so that said tongue and platform may have pivotal movement in relation to each other. Laterally and rearwardly extending feet rests 12 are formed on the enlarged portion 11 of the draft tongue 10 and provide a construction whereby the operator or driver may cause the device to travel at an angle in relation to the line of draft thus easily guiding the device along a row of beets. 90

Blades 13 are secured to the vertical rods 6 and are inclined in the direction of their rear ends so that the forward ends may readily pass under the tops of the beets and gradually raise them as the machine or device moves forwardly. Rearwardly extending 100 guide members 14 are pivoted for lateral movement to the rear ends of the blades 13 and have their rear ends pivotally connected by a transverse brace 15. The guide members 14 are constructed from flexible metal and have their inner edges converging as illustrated at 16 to guide the beet tops into engagement with circular knives 17 carried by the rear portion of the guide members 14 and which are located in close proximity to 110 each other so that the beet tops passing rearwardly to the guides will be severed from

the beets. The guide members being constructed from flexible metal will permit the same to readily flex and pass over beets of different heights and sizes and the pivotal 5 connection between the guide members at their rearward ends and also the pivotal connection between the guide members and the blades permit said guide members to shift laterally so as to readily follow out 10 the row of beets.

One of the arms 2 extends rearwardly further than the other arm and has formed thereon a segmental rack 18 which is associated with a pivoted controlling lever 19. 15 The controlling lever 19 has its upper end or handle disposed in close proximity to the seat 4 so that the operator can readily actuate the same while the lower end extends in a plane below the platform and 20 has journaled thereto a shaft 20. A latch dog 21 is carried by the lever 19 and is controlled by a grip on the handle of the lever, whereby said lever may be locked in various adjusted positions by permitting 25 the latch dog to engage the teeth of the segmental rack 18.

A reel 22 is secured to the shaft 20 and is disposed directly over the guides 14 and consists of a hub 23 provided with radially 30 extending spokes 24 on which are formed transversely disposed fingers 25 adapted during the rotation of the reel to engage the beet tops when passing through the guide elements 14 and force and hold them into 35 engagement with the knives so that during the forward motion of the device the beet

tops will be severed by the knives. A sprocket gear 26 is secured to the shaft 20 and has trained over the same an endless chain 27 that is in turn trained over a 40 sprocket 28 secured to one of the ground wheels 8 whereby the reel is driven by the forward motion of the device.

While I have shown and described the preferred embodiment of my invention, it 45 will be understood that minor changes in construction, combination, and arrangement of parts may be made without departing from the spirit and scope of the invention as claimed.

Having thus described my invention what I claim is:

A beet topper including a supporting structure, upwardly and rearwardly inclined blades carried by said supporting structure 55 and adapted to lift beet tops from engagement with the ground, flexible guide members extending rearwardly from the blades and having pivotal connection therewith and adapted to receive the tops from said 60 blades, said members converging towards their rear ends and having said ends spaced and pivotally connected with each other, circular knives carried by said members and means for forcing the tops in contact with 65 the knives.

In testimony whereof I affix my signature in presence of two witnesses.

STEPHEN A. GOODSON.

Witnesses:

EDWARD H. McDOWELL,
JOHN T. SHINDLER.
